COMBINATION COAL-FED WATER HEATER

William K. Staley, Morton, Pa., assignor to Anthracite Industries, Inc., New York, N. Y., a corporation of Delaware

Application July 22, 1938, Serial No. 220,615

4 Claims. (Cl. 126—344)

The present invention relates generally to the automatic stoking and burning of coal and more particularly to a unitary apparatus for supplying fuel to and maintaining combustion in a burner or retort of smaller dimensions and capacity than any heretofore devised and which functions in the open air instead of being confined in a combustion chamber.

In heating apparatus as heretofore in use it has been possible during the past several years, to more or less successfully burn coal in a retort located in a furnace or enclosed combustion chamber, such coal being supplied thereto automatically by means of a stoker from a bin or hopper as the case may be. Where the burner is enclosed, as in the ordinary house heating boiler or furnace, quite efficient operating results have been obtained provided the correct grade of anthracite, such as buckwheat or rice grades, is delivered to the bin or hopper. Such automatic equipment, however, is applied to comparatively airtight furnaces, all air supplied being furnished by means of mechanical draft, and is furthermore adapted for the use of anthracite of larger size than barley. In consequence a wide field of commercial use has been forced to await the solution of the problem of open air use with cheap fuel. This field includes water heaters for domestic use and no one heretofore has been able to produce a coal stoking and burning unit so associated and combined with the ordinary gas fuel type of water heater (minus the gas burner) which is practical or commercial. It would seem a very simple thing to pattern a small burner and its stoker after its well known large counter-part so that the miniature device could be used for water heaters, which are relatively small as compared to furnaces, boilers and like heating units, but this is not the case. When such reduction in size was tried, the result was failure. Thus the dwarf burner and stoker refused to function with any grade of coal which had worked satisfactorily in the known types of burners and stokers. This was surprising and baffling. Continued experiments finally gave a clue to success in the use of barley size coal which has long since been abandoned as a practical fuel for mechanically fired domestic burners. Its use however did not come from a mere substitution of one fuel for another, but in conjunction with a complete reorganization of the coal feeding means including an ingenious balancing of rate of feed, control of feed by water temperature, forced draft, and the mixing of the gaseous products with a supplemental supply of

air. All of these in association with the unit to which the burner was applied were the factors which led to success.

Some of the objects of the present invention are to provide a coal burner and mechanical feed for use with a heater unit to supply hot water for home use or the like; to provide a coal burning unit of the automatic type which will efficiently burn barley size coal; to provide an improved mechanical feed for a coal burning unit; to provide an improved control for a mechanical coal feed wherein the rate of feed bears a direct relation to the size of fuel and the heating effect thereof; to provide a novel dual air supply for a stoker wherein a main air supply furnishes air for combustion purposes and a supplemental air supply furnishes air to temper the heated products and make it possible to effectively control the temperature of the water or other medium being heated; and to provide other improvements as will hereinafter appear.

In the accompanying drawings, Figure 1 represents a side elevation of one form of the invention in association with a hot water heating system; Figure 2 represents a side elevation of the burner and fuel feed mechanism; Figure 3 represents an end elevation of Figure 2; Figure 4 represents a detail in plan of the burner; Figure 5 represents a sectional detail of one form of the thermostat; and Figure 6 represents a section on line 6—6 of Figure 1.

Referring to the drawings one form of the present invention consists of a coal burning unit 10 arranged to be mechanically supplied with fuel by a stoker 11 from a superposed hopper 12. The unit 10 is shown in combination with a coil water heater 13 of the well known gas heated type but from which the gas burner has been removed. In the illustrated form of the invention the heater 13 maintains a supply of hot water in a storage tank 14 which is connected by circulating pipes 15 and 16 with the coil 17 of the heater 13. It should be noted that the burner unit 10 is not only located well below the coil 17 but is exposed on all sides to the atmosphere and hence operates under very unusual conditions. Furthermore since the casing of a domestic water heater is of relatively small diameter, the diameter of the burner unit 10 must also be restricted being therefore of the order of approximately seven inches. In effect it becomes a miniature coal burner which through an ingenious association with an inlet flue 18 has been made to operate under the most adverse conditions for this type of equipment. As shown

the flue 18 is of truncate shape and is located between the coaxially positioned heater 13 and the unit 12. The large diameter of the flue 18 is considerably larger than the diameter of the unit 10 in order to form an annular passage 20 about the rim of the unit 10 as a means for mingling fresh air with the burning products. This tempering of the products of combustion has been found to be one of the major requirements for efficient operation of the unit 10 and heater 13 as a unitary combination.

Referring to the burner unit 10, a retort 21 in the form of a funnel shaped casting is provided having a circular flange which seats upon the top face of the base bowl 22. The parts thus assembled are held in place by cotter pins 23. This is a simple and convenient assembly which is made possible by like material in the two castings whereby warping of one part with respect to the other is avoided. The funnel part of the retort 21 is provided with a plurality of circumferentially arranged rows of tuyères 24, those nearest the outlet end of the funnel part being of somewhat smaller diameter than the remaining rows. This avoids undue loss of air near the surface of the burning fuel.

The bowl 22 is provided with a fuel inlet 25 and an air inlet 26, the former leading directly to the inlet end of the retort 21, and the latter discharging into a chamber 27 which surrounds the inlet 26 and the perforated funnel part of the retort 21. A removable plate 28 in the bottom of the bowl 22 permits the cleaning out of any collection fines or sediment when necessary.

For supplying air under forced draft to the air inlet 26, an air supply pipe 30 leads from the inlet 26 to the discharge side of a fan housing 31 which is located below the hopper 12 and adjacent a motor 32, the drive shaft 33 of which drives the blower fan 34.

For supplying fuel to the inlet 25, a conduit 35 leads from the inlet 25 to and communicates with the downwardly flared hopper bottom 36. A suitably mounted feed screw 37 of slow feed pitch is arranged within the conduit 35, and its shaft 38 projects from the closed end of the conduit 35 to receive a driven ratchet wheel 40. A spring pressed pawl 41 is pivotally mounted to ride upon the ratchet wheel 40 to thereby prevent back lash.

In order to actuate the ratchet wheel 40 for step by step feed and to regulate the step quantity according to water temperature conditions, a work pawl 42 is pivotally mounted on the short arm of a rock lever 43 in position to engage the ratchet wheel 40. The lever 43 is freely oscillatable on the shaft 38 and has its long arm in the plane of rotation of a roller 44 carried by a crank arm 45. A flat strip spring 46 is attached at one end to the lever 43 while its free end curves out of contact with the lever 43 but into contact with the roller 44. This provides a yielding pick-up for the crank arm 45 to eliminate impact noise and reduce wear. A coil spring 47 is stretched being a fixed point 48 and the lever 43 to return the lever 43 after a ratchet working stroke.

As a means for varying the stroke of the lever 43 in accordance with the temperature of the water heated, a link chain 50 connects the lever 43 with a rock arm 51 which is fixed to a rock shaft 52. An operating arm 53 is also fixed to the shaft 52 and is joined to one end of a suitable flexible cable or chain 54, the other end of which is attached to the long arm of a control lever 55 which is pivoted in a bracket 56 attached

to the housing of an expansion type of thermostat 57. The short arm of the lever 55 enters the thermostat housing to seat against an expansion member 58 for actuation thereby. The action of the thermostat can be varied by means of a weight 60 adjustable on the long arm of the control lever 55, and arranged to be set in a selected position by a clamping screw 61.

Attention is directed to the fact that the motor 32 is of the type which can be stalled for an indefinite period without burning of the motor windings, for example a motor of the shaded pole type has been found to give satisfactory results. Associated with this motor unit is the mechanical drive which is designed sufficiently strong to stall the motor in case of a jam to thus save the mechanical parts from injury. Such jams may be caused by foreign matter, such as nails, screws, nuts and the like, or large size coal accidentally entering the coal worm. By this construction it is unnecessary to use shear pins or similar devices to prevent injury when the feed becomes obstructed. Also it should be noted that the motor and gear box constitute a driving unit which can be replaced by simply removing the four holding capscrews. Furthermore the coal worm, thrust bearing and ratchet assembly form a complete driven assembly which can be removed as a unit for replacement.

It will now be apparent that a novel combination of water heater and coal burning unit has been devised wherein barley size coal can be successfully and efficiently used for heating water for domestic use. It should be noted that small quantities of coal in process of combustion possess no banking characteristics and therefore when once ignited must be kept replenished as consumed, which necessitates a continuously operating feeding means. Such continuous feed, even though regulated for a minimum and maximum feed, tends to overheat the water and in order to avoid too high water temperature (while at the same time maintaining efficient operation) a novel supplemental air supply means has been created to temper the hot products from the burner according to operating conditions.

Having thus described my invention, I claim:

1. A combination of a water heater consisting of a water circulating coil and a tubular casing enclosing said coil for the passage of products of combustion, said casing being arranged to discharge gases at its upper end and open to the atmosphere at its lower end, a burner unit coaxially located below said casing, means for feeding coal continuously to said unit, a forced draft 55 to supply air only to said unit, means to vary the rate of coal feed according to the water temperature, and an inlet for air at atmospheric pressure to said casing, said inlet being so associated with said casing and said unit that the 60 quantity of supplemental air traversing said inlet is controlled by the pressure of the gaseous products in said casing whereby under pilot conditions of said burner unit the efficiency of heat transfer from the products of combustion is 65 reduced.

2. The combination with an enclosed water heater having an open bottom to receive products of combustion to heat the water, of a continuously operable coal burning unit to produce the 70 products of combustion, means for feeding fuel to said unit at a varying rate in accordance with heat demand of the water to be heated, a forced draft mechanism to supply a non-variable volume of air to said unit, and means to vary 75

the thermal efficiency of the products of combustion in the heater to maintain combustion in the burner unit under pilot conditions without overheating the water including a supplementary supply of air under atmospheric pressure fed directly into said heater at a point above and in non-combustive relation to said unit.

3. A replacement burner unit for a gas fired water heater consisting of a coal burning retort, means for feeding coal continuously to said retort, a forced draft to supply air to said retort, means responsive to the temperature of the water being heated to vary the rate of fuel feed, and means including a supplemental air supply delivered directly into said heater at a point above and in non-combustive relation to said

retort to prevent overheating of the water when said fuel feed is functioning at a minimum rate.

4. The combination of a water heater and a coal burning unit, said heater including a casing forming a combustion chamber open at the bottom and a water coil in said chamber, said unit being disposed coaxially below said bottom, means forming an annular passage about said unit to admit air to said chamber according to pressure conditions in said chamber to vary the efficiency of heat transfer from the products of combustion to the water in said coil, means for feeding fuel to said unit, and a forced draft mechanism to supply air only to said unit to support combustion.
